*Nathaniel Waterman's Ornamental Design for the half plate of a Wattile Baker,
Entered July 26, 1853.*

Dec 578

Nath'l Waterman, of Boston, Mass.

Letters Patent No 578 Dated July 5th 1853.

The schedule, referred to in these Letters Patent and making part of the same

To all persons to whom these presents shall come-

Be it known that I, Nathaniel Waterman, of Boston, in the County of Suffolk, and State of Massachusetts, have invented or produced a new ornamental configuration or design for the half plate of a waffle baker, and I do hereby declare that the same is fully represented by the accompanying drawings, of which,

Figure 1. is a plan of the said plate - and

Figure 2. is a section of it taken on a line from A. to B. of Figure 1. In the said drawings, which make part of this my specification.

C, denotes a circular plate having a rim D, extending around it and connected by two crossed bars E, F, that are arranged at right angles to one another at the middle of the plate - within, and near to, the rim are raised letters in reverse, they being those of the words, Faith, Mercy, Truth, and Grace, one of the said words, being represented in each quadrant, within which latter are also numerous frustropyramidal projections as seen at a, a, &c, that are elevated on the plate, the whole under the form as seen in the drawings constituting the design or configuration which is the subject of my invention.

I claim the design for the waffle plate, or mould substantially as exhibited in the drawings.

In testimony whereof, I have here to set my signature
